(57) CLAIM

I claim, the ornamental design for a bag organizer, as shown and described.

DESCRIPTION

FIG. 1 is a perspective view of the bag organizer shown in a closed orientation with handles of the plastic bags extended from the interior of the bag organizer.

FIG. 2 is a front elevation view of the bag organizer.

FIG. 3 is a top overhead view of the bag organizer.

FIG. 4 is a side elevation view of the bag organizer.

FIG. 5 is a bottom view of the bag organizer; and,
FIG. 6 is a perspective view of the bag organizer shown in an opened orientation.

The broken line showing of the bag organizer is included for the purpose of illustrating portions of the article, and forms no part of the claimed design.
